A. McOmber,

Artificial Arm.

U. S. 60,921.

Patented Jan. 1, 1867.

United States Patent Office.

ABNER McOMBER, OF SCHENECTADY, NEW YORK.

Letters Patent No. 60,921, dated January 1, 1867.

IMPROVEMENT IN ARTIFICIAL ARMS.

The Schedule referred to in these Letters Patent and making part of the same.

TO ALL WHOM IT MAY CONCERN:

Be it known that I, ABNER McOMBER, of Schenectady, in the county of Schenectady, and State of New York, have invented an improved Artificial Arm; and I do hereby declare that the following is a full, clear, and exact description thereof, reference being had to the accompanying drawings, making a part of this specification, in which—

Figure 1 is a perspective view of the improved artificial arm complete.

Figure 2, shows the upper portion of the arm with the hand removed.

Figure 3 is a perspective view of the hand.

Figure 4 is a sectional view showing the spring thumb and latch, and the mode of connecting the hand to the artificial stump.

Figure 5 is a sectional view of the end of the stump, showing the mode of attaching a writing instrument thereto.

Similar letters of reference indicate corresponding parts in the several figures.

The main object of this invention is to so construct an artificial arm that the hand, or the lower section of the arm, or both, may be readily detached, and a writing instrument applied to the stump for the purpose of affording the wearer a better control of such writing instrument than he would have if it was secured to the hand, as will be hereinafter described. Another object of my invention is to provide a spring thumb of an artificial hand with a spring latch and releasing pin, in such manner that the wearer of such hand can more conveniently apply a fork, a knife, or other article between the thumb and fingers and remove the same therefrom, than can be done with artificial hands hitherto constructed, as will be hereinafter described.

To enable others skilled in the art to understand my invention, I will describe its construction and operation.

The artificial arm which I have represented in the accompanying drawings is designed for a person having a stump which is amputated below the elbow, but the invention for holding a writing instrument is applicable to stumps amputated above the elbow, as will be hereinafter shown.

The arm shown in the drawings consists of three sections: The hand A, the lower arm section B, and the sleeve or strap C. The hand section, A, terminates at the wrist, and has an elliptical plate, *a*, secured to it by screws or otherwise, from which project two tongues, *b b*, having eyes through them for receiving a pin, *c*, by which the hand is secured to the stump or section, B. These tongues are arranged diametrically opposite each other, and enter slots, *b' b'*, which are made through the elliptical plate, *d*, which is secured to the wrist of the section B, as shown in figs. 2 and 4. The plate *a* also has two oblong slots, *e e*, made through it which are diametrically opposite each other across the longest part of the plate, for receiving spring clasps *g g'*, that are applied to the plate *d*, as shown in figs. 2 and 5. The clasp, *g*, is made in the form of an open link, as shown in fig. 6, and inserted into an oblong slot in plate *d*, and prevented from being drawn out of place by the pin, *i*. The lower clasp, *g'*, is formed on a long shank, as shown in fig. 7, which enters a slot in plate *d*, and is secured in place by means of a set-screw, *j*, as shown in fig. 5. The set-screw *j* admits of the clasping portion *g'* being adjusted and set at different distances from the plate *d*, according to the angle at which it is desired to secure the writing instrument to the section B. The open ends or jaws of the clasp *g* spring outwards, and are made to clasp and hold a pen or pencil handle by pressing this clasp inward; the lower clasp *g'* clasps the pen or pencil handle by its elastic action. To use the devices for holding the writing instrument it is only necessary to withdraw the pin *c*, which passes through the eyes of the tongues *b b*, and remove the hand section A. I do not confine this part of my invention to the lower arm section B, as it may be applied substantially in the same manner to upper arm sections, where a person has had his arm removed above the elbow. Nor do I confine my invention to the precise devices herein described for securing a writing instrument to the stump of an artificial arm, as other forms of clasps or holders may be adopted which will answer the purpose. I prefer to employ self-holding clasps, as they will be found more convenient than other forms. The second part of my invention consists in the employment of a spring thumb, *D*, which is pivoted at *k* to the hand A, and acted upon by an India-rubber spring, *l*, or any other suitable spring which will keep it closed, as indicated in black lines, fig. 4. The object of this spring *l* is to press or draw the cushion of the thumb down forcibly upon a fork or a knife, and assist in holding such instrument between it and the fingers. A long spring, *m*, is secured at one end to the interior of the thumb *D*, carried back over a transverse pin, *n*, on the hand, and passed under a transverse pin, *p*. This

spring m has a latch, m' , formed on it near its rear end, which will catch in front of pin p , when the thumb is opened or lifted up, and hold the thumb in this position, as indicated in red lines, fig. 4. A pin, s , is inserted loosely through the ball of the thumb, so as to touch the spring m near its latch, by means of which the latch m' can be released from its pin p , and the thumb allowed to close upon the instrument which is applied to the hand. The object of applying a spring latch to a spring thumb is to allow the person wearing an artificial hand to introduce anything between the thumb and fingers of such hand without the inconvenience of having to hold open the thumb at the same time. The spring latch will hold the thumb open, and allow of the adjustment of a knife, a fork, or any other thing between the thumb and fingers in the proper position, after which the pin s is pressed upon, and the thumb allowed to grasp and hold such thing. In fig. 1, I have shown at t a screw socket for receiving a male screw formed on the end of a knife or fork, and assisting in securing such instrument to the hand A . The thumb D is held open by the latch m' while such instrument is screwed into the socket t .

I do not wish to be understood as laying claim to a spring thumb, as artificial hands have been constructed with spring thumbs before my invention.

Having described my invention, what I claim as new, and desire to secure by Letters Patent, is—

1. The permanently attached clasps $g g'$, on the stump section of the arm, in combination with the slotted plate $a e e$, of the opposite section, substantially as and for the purpose set forth.
2. The application to a spring thumb of an artificial hand, of a latch, or its equivalent, for holding said thumb open when desired, and means for releasing the thumb from the latch, substantially as described.

ABNER McOMBER.
